UNITED STATES PATENT OFFICE

90,782

DESIGN FOR LEATHER SUSPENDERS

Lowell W. Shields, Rochester, N. Y., assignor
to Hickok Manufacturing Company, Inc.,
Rochester, N. Y., a corporation of New York

Application July 17, 1933. Serial No. 48,748

Term of patent 3½ years

To all whom it may concern:

Be it known that I, LOWELL W. SHIELDS, a citizen of the United States, residing at Rochester, in the county of Monroe and State of New York, have invented a new, original, and ornamental Design for Leather Suspenders, of which the following is a specification, reference being had to the accompanying drawing, forming part thereof.

In the drawing:

The figure is a front view of leather suspenders, showing my new design.

I claim:

The ornamental design for leather suspenders, as shown.

LOWELL W. SHIELDS.
